Charles A. Culligan

UNITED STATES PATENT OFFICE.

CHARLES A. CULLIGAN, OF PENNIAC, NEW BRUNSWICK, CANADA.

INSULATOR-PROTECTOR.

1,280,172.

Specification of Letters Patent.

Patented Oct. 1, 1918.

Application filed February 16, 1918. Serial No. 217,721.

To all whom it may concern:

Be it known that I, CHARLES A. CULLIGAN, a subject of the King of Great Britain, residing at Penniac, in the Province of New 5 Brunswick and Dominion of Canada, have invented certain new and useful Improvements in Insulator-Protectors, of which the following is a specification.

- Telephone, telegraph, and other electrical 10 conducting wires are usually attached to insulators which are mounted upon poles and other supporting means. These insulators are frequently used as targets by mischievous persons, and as a consequence, such insulators are frequently broken, thereby permitting the wire strung thereon to become detached and fall, and oftentimes resulting in a fatality particularly when the current carried thereby is of high voltage.
- 20 The present invention has for its primary purpose to protect the insulators of aerial-strung electrical conducting wires, while at the same time insuring complete insulation of the conductor to prevent loss of current.
- 25 The drawing illustrates a preferred embodiment of the invention, however, it is to be understood that in adapting the same to meet different conditions, various changes in the form, proportion, and minor details of 30 construction may be resorted to without departing from the nature of the invention as claimed hereinafter.

In the drawings:

Figure 1 is a view in elevation of the 35 upper portion of a pole provided with insulator protecting means embodying the invention.

Fig. 2 is a view similar to Fig. 1 with the 40 protector and insulator in central section.

Fig. 3 is a section on the line 3—3 of Fig. 1 looking to the left as indicated by the arrows.

Corresponding and like parts are referred to in the following description and indicated in the several views of the drawings by like 45 reference characters.

The numeral 1 designates a pole such as commonly employed for aerial-strung telephone and telegraph wires.

The protector is of sectional formation 50 and comprises the parts 2 and 3 which are separable on a vertical line. The part 2 is attached to the pole or other supporting means 1 and the part 3 is hingedly connected to the part 2 so as to swing outwardly and

downwardly from its upper end. The hinge 55 connection between the parts 2 and 3 is indicated at 4 and is inserted so as to be partially protect'd. The upper ends of the parts 2 and 3 are inclined so as to shed water and prevent the lodgment of any material there- 60 on. In practice, the protector may be constructed of any suitable material according to location and as found best adapted to meet specific requirements. Usually, wood has been found to meet all requirements be- 65 cause of its cheapness and the ease with which it may be worked. However, it is to be understood that the protector may be molded or pressed from any suitable plastic material.

In forming the protector, the part 2 which is secured to the post or support 1 is adapted to have the insulator 5 attached thereto, and the part 3 constituting the cover is recessed upon its inner face to receive the outer or 75 projecting end of the insulator. The insulator 5 may be of usual formation and constructed of glass or other vitreous material and is internally screw-threaded to make connection with a pin 6, which is formed as a 80 part of the section 2. The part 2 is recessed in its outer face as indicated at 7, such recess being of ample proportion to receive the insulator and admit of the conducting wire 8 being readily attached thereto. The 85 base portion of the pin 6 is reduced, and an enlarged portion 9 is formed at the bottom of the recess 7 to insure a substantial connection being obtained between the pin and the part 2 of which it preferably constitutes 90 an integral part. While bolts 10 are disclosed as fastening means for securing the protector to the support 1 it is to be understood that any suitable attaching means may be employed.

The part 3 constituting the cover is formed upon its inner face with a recess 11 to match with the recess 7 and receives the outer end of the insulator 5. The faces of the parts 2 and 3 are adapted to make close 100 contact so as to exclude moisture. Notches or grooves 12 are formed in the edges of the parts 2 and 3 at the sides of the recesses, and the notches or grooves initially form openings for the passage of the electrical conductor 8 when the cover 3 is closed against the part 2. Suitable fastening means hold the cover in closed position and, as

shown consist of hooks 13 and eyes 14. The hooks by preference are attached to the upper portion of the part 3 and are adapted to engage the eyes 14 which are carried by the part 2.

5 It will be understood from the foregoing, taken in connection with the accompanying drawing that the invention provides a protector for closing the insulators of aerial-strung electrical conductors which will prevent such insulators from being broken when used as targets, such protector being of simple structure capable of being cheaply manufactured and easily and quickly placed in position, and serving at the same time as supporting means for the insulator thereby obviating the use of the ordinary pin or arm upon which the insulator is generally mounted.

10 20 What I claim is:

1. A protector for the insulator mountings of electrical conducting wires, the same comprising separable parts which are adapted to receive and inclose the insulator, and one 15 of such parts being provided with a support upon which the insulator is mounted, said

support forming an integral portion of the part carrying the same.

2. A protector for the insulator of an electrical conductor such protector comprising complementary parts having matching recesses in their meeting faces and one of such parts having an integral insulator support projecting from the bottom thereof, and said parts having opposite openings for the 30 35 passage of the electric wire adapted to be bound upon the insulator.

3. An insulator protector comprising complementary parts hingedly connected at one end and having matching recesses in their 40 meeting faces, and one of the parts having an integral insulator support, and said protector having opposite openings for the passage of the electric conducting wire.

In testimony whereof I affix my signature 45 in presence of two witnesses.

CHARLES A. ^{his} X CULLIGAN.
